UNITED STATES PATENT OFFICE.

JAMES M. WOODMAN, OF WAUKEGAN, ILLINOIS.

DISPLAY CARTON.

Application filed March 10, 1921. Serial No. 451,151.

To all whom it may concern:

Be it known that I, JAMES M. WOODMAN, a citizen of the United States, residing at Waukegan, county of Lake, State of Illinois, have invented a certain new and useful Improvement in Display Cartons, and declare the following to be a full, clear, and exact description of the same such as will enable others skilled in the art to which it pertains to make and use the same, reference being had to the accompanying drawings, which form a part of this specification.

My invention has for its object to produce a simple and novel carton provided with an attachment which will not interfere with the use of the carton as a container for shipping goods and at the same time will permit the carton to be firmly supported in an inclined position with the lid held in place as a display card in such a manner that it will not accidentally become displaced even though the carton be moved about from one position to another.

The various features of novelty whereby my invention is characterized will herein-after be pointed out with particularity in the claims; but, for a full understanding of my invention and of its object and advantages, reference may be had to the following detailed description taken in connection with the accompanying drawings, wherein:

Figure 1 is a side elevation of a carton arranged in accordance with a preferred form of my invention, adjusted so as to serve as a display case;

Fig. 2 is a vertical section through the carton illustrated in Fig. 1, along a plane parallel to the side appearing in Fig. 1;

Fig. 3 is a rear end elevation of the carton as it appears in Fig. 1;

Fig. 4 is a top plan view of the carton, on an enlarged scale, showing the same closed, a corner of the upper portion of the carton being broken away;

Fig. 5 is a side elevation of the carton as it appears in Fig. 4; and

Fig. 6 is a plan view of a blank out of which my improved carton may be made.

Referring to the drawings, 1 and 2 represent the sides, 3 and 4 the ends, and 5 the bottom of a carton of any usual or suitable construction. The lid of the carton is hinged at one end to the upper edge of the end wall, 3, and is of a size and shape to extend across the entire open top of the carton. The lid is preferably divided into

two sections, 6 and 7, arranged end to end by means of a transverse crease indicated by the dotted line, 8, in Fig. 4, whereby the free end of the lid may be folded back upon the rear or inner half. Forming a continuation of the lid proper is a section, 9, of the same dimension, measured in the direction of the length of the lid, as the height of one of the end walls. Consequently, when the lid is closed, the part 9 may be folded downwardly against the outer face of the end wall, 4, and, when the lid is folded upon itself and is swung into a more or less upright position as shown in Figs. 1 and 2, the member 9 will lie against the outer face of the other end wall, 3. On the end of the section 9 is attached a device which, when the lid is opened and placed in a display position, may be swung underneath the rear end of the carton and cause the carton to assume an inclined position in which the contents will be more favorably displayed than when the carton

is resting flat on a table or counter. This device may take a variety of forms, but is preferably so constructed that when the lid is closed the device will lie snugly against the carton so as not materially to increase the size of the latter or interfere with the convenient handling or storing of the carton.

These ends may conveniently be attained by making the supporting device in the form of a flap, 10, of any desired length, this flap being folded underneath and in contact with the bottom of the carton, when serving as a support, and having two side flanges, 11 and 12, and an end flange or wall, 13, connected together and projecting at right angles therefrom; the flanges

serving as supporting feet when the carton is being used as a display case, and simply lying close against one end wall and the two side walls of the carton when the carton is closed. The part 10 is preferably provided with a hole, 14, extending through the same in position to receive a tongue, 15, struck downwardly from the bottom wall of the carton so that the supporting device may be locked to the carton when the latter is to be used as a display case. As heretofore stated, the flap 10 may be made of any desired length but, since in each of its two working positions it lies against the bottom of the carton, it

may be made as long as the carton itself. The flange, 13, may have a depth or height

2
equal to the depth or height of the carton, and the flanges 11 and 12 may be made wedge-shaped, decreasing gradually in height from the flap 13 to a vanishing point at the free end of the flap 10 if the latter flap be of the same length as the carton. When the parts are proportioned in this way, the carton presents an extremely neat appearance when set up as a display case, because its side and end walls will present unbroken surfaces from the upper edge of the carton to the plane of the supporting surface, giving the structure a rigid substantial appearance.

15 In Fig. 6 I have shown a blank out of which my improved carton may conveniently be made, when it is desired to make it out of a single piece of material. It will be seen that the blank consists of a central panel 20 containing in the order named the flap 10, the section 9, the lid sections 7 and 6, the end section 3, the bottom section 5, the end section 4, and an auxiliary end flap, 16, adapted to be folded inwardly of the carton and 25 lie against the inner face of the end 4. At the sides of the flap, 10, are the wedge-shaped flange sections, 11 and 12. At the inner ends of the flanges 11 and 12 are wings, 17 and 18, which are adapted to overlap and form the rear foot or flange, 13, of the supporting device; the part 17 being provided with a slot, 19, and the part 18 having a notch, 20, cut into the same to permit the parts 17 and 18 to be interlocked with each 30 other. At the ends of the end section 3 are flaps, 21 and 22, respectively, adapted to be folded inwardly so as to lie against the inner faces of the side walls, 1 and 2, of the carton. The end section, 4, is provided with flaps, 23 35 and 24, similar to the flaps 21 and 22. At the sides of the bottom section, 5, are the end sections 1 and 2 each of which is provided with an extension, as indicated at 25 and 26, respectively, adapted to be folded inwardly. It will be seen that in assembling the body of the carton the sections 3 and 4 are bent upwardly at right angles to the section 5; the four flaps, 21, 22, 23 and 24, are then bent at right angles to the end sections 3 and 4; the side sections 1 and 2 are then bent 40 upwardly at right angles to the bottom section; and the flanges 25 and 26 are folded inwardly and downwardly over the flaps 21, 22, 23 and 24 so as to house the latter between 45 the flaps 25 and 26 and the side walls 1 and 2.

While I have illustrated and described with particularity only a single preferred form of my invention, I do not desire to be limited to the exact structural details thus illustrated and described; but intend to cover all forms and arrangements which come within the terms employed in the definitions of my invention constituting the appended 50 claims.

I claim:

1. A carton having a lid hinged thereto at one end, said lid being foldable upon itself along a line parallel with the hinge, and a part in the form of a box closed on four 70 sides only attached to the free end of the lid in position to be nested about the bottom and one end of the carton when the lid is closed and to be stationed underneath the other end of the carton when the lid is opened and 75 folded back upon itself, so as to support the carton in an inclined position and hold the folded lid in a more or less upright display position.

2. A carton having a lid hinged thereto at 80 one end, said lid being foldable upon itself about a line parallel with said hinge and approximately midway between the ends of the lid, said lid having at its free end an extension of the same length as the height of the 85 carton, and a device attached to the end of said extension and adapted to be nested upon the bottom and one end of the carton when the lid is closed and to be swung underneath the opposite end of the carton when the lid 90 is opened and folded back upon itself so as to support the carton in an inclined position and hold the folded lid in a more or less upright display position.

3. A carton having a lid hinged thereto 95 at one end, said lid having at its free end an extension of the same length as the height of the carton, a flap connected to the free end of said extension, said flap having at three edges only connected flanges extending 100 at right angles therefrom, said lid being foldable upon itself along a transverse line approximately midway between its ends, the parts being so proportioned and arranged 105 that when the lid is closed said extension overlies one of the ends of the carton while said flap lies underneath the bottom of the carton and its flanges lie respectively against the sides of the carton and between said extension and the adjacent end, while when the lid is opened and folded upon itself said extension lies against the opposite end of the carton and said flap lies underneath the carton in such a position that its flanges 110 are directed downwardly and serve as a 115 support for the carton.

4. A carton having a lid hinged thereto at one end, said lid having at its free end an extension of the same length as the height of the carton, a flap connected to the free end of said extension, said flap having at three edges connected flanges extending at right angles therefrom, said lid being foldable upon itself along a transverse line approximately midway between its ends, the parts being so proportioned and arranged 120 that when the lid is closed said extension overlies one of the ends of the carton while said flap lies underneath the bottom of the carton and its flanges lie respectively against 125 the 130

- the sides of the carton and between said extension and the adjacent end, while when the lid is opened and folded upon itself said extension lies against the opposite end of the carton and said flap lies underneath the carton in such a position that its flanges are directed downwardly and serve as a support for the carton, said flap having a hole therein, and the bottom of the carton having a tongue adapted to enter said hole when said flap is in the last named position and lock said flap to the said bottom.
5. A carton having a lid hinged thereto at one end, said lid having at its free end an extension of the same length as the height of the carton, a flap connected to the free end of said extension, said flap having at three edges connected flanges extending at right angles therefrom, said lid being foldable upon itself along a transverse line approximately midway between its ends, the parts being so proportioned and arranged that when the lid is closed said extension overlies one of the ends of the car-
- ton while said flap lies underneath the bottom of the carton and its flanges lie respectively against the sides of the carton and between said extension and the adjacent end, while when the lid is opened and folded upon itself said extension lies against the opposite end of the carton and said flap lies underneath the carton in such a position that its flanges are directed downwardly and serve as a support for the carton, said flap having a hole therein, the bottom of the carton having a tongue adapted to enter said hole when said flap is in the last named position and lock said flap to the said bottom, said flap being of substantially the same length as the carton, and the side flanges on the flap extending the entire length of the latter and decreasing gradually in height from one end to vanishing points at the free end of the flap.
10. A carton having a lid hinged thereto at one end, said lid having at its free end an extension of the same length as the height of the carton, a flap connected to the free end of said extension, said flap having at three edges connected flanges extending at right angles therefrom, said lid being foldable upon itself along a transverse line approximately midway between its ends, the parts being so proportioned and arranged that when the lid is closed said extension overlies one of the ends of the car-
- ton while said flap lies underneath the bottom of the carton and its flanges lie respectively against the sides of the carton and between said extension and the adjacent end, while when the lid is opened and folded upon itself said extension lies against the opposite end of the carton and said flap lies underneath the carton in such a position that its flanges are directed downwardly and serve as a support for the carton, said flap having a hole therein, the bottom of the carton having a tongue adapted to enter said hole when said flap is in the last named position and lock said flap to the said bottom, said flap being of substantially the same length as the carton, and the side flanges on the flap extending the entire length of the latter and decreasing gradually in height from one end to vanishing points at the free end of the flap.
15. A carton having a lid hinged thereto at one end, said lid having at its free end an extension of the same length as the height of the carton, a flap connected to the free end of said extension, said flap having at three edges connected flanges extending at right angles therefrom, said lid being foldable upon itself along a transverse line approximately midway between its ends, the parts being so proportioned and arranged that when the lid is closed said extension overlies one of the ends of the car-
- ton while said flap lies underneath the bottom of the carton and its flanges lie respectively against the sides of the carton and between said extension and the adjacent end, while when the lid is opened and folded upon itself said extension lies against the opposite end of the carton and said flap lies underneath the carton in such a position that its flanges are directed downwardly and serve as a support for the carton, said flap having a hole therein, the bottom of the carton having a tongue adapted to enter said hole when said flap is in the last named position and lock said flap to the said bottom, said flap being of substantially the same length as the carton, and the side flanges on the flap extending the entire length of the latter and decreasing gradually in height from one end to vanishing points at the free end of the flap.
20. A carton having a lid hinged thereto at one end, said lid having at its free end an extension of the same length as the height of the carton, a flap connected to the free end of said extension, said flap having at three edges connected flanges extending at right angles therefrom, said lid being foldable upon itself along a transverse line approximately midway between its ends, the parts being so proportioned and arranged that when the lid is closed said extension overlies one of the ends of the car-
- ton while said flap lies underneath the bottom of the carton and its flanges lie respectively against the sides of the carton and between said extension and the adjacent end, while when the lid is opened and folded upon itself said extension lies against the opposite end of the carton and said flap lies underneath the carton in such a position that its flanges are directed downwardly and serve as a support for the carton, said flap having a hole therein, the bottom of the carton having a tongue adapted to enter said hole when said flap is in the last named position and lock said flap to the said bottom, said flap being of substantially the same length as the carton, and the side flanges on the flap extending the entire length of the latter and decreasing gradually in height from one end to vanishing points at the free end of the flap.

In testimony whereof, I sign this specification.

JAMES M. WOODMAN.
